(74) Attorney, Agent, or Firm — Sheridan Ross P.C.

(57) **CLAIM**

The ornamental design for a nozzle, as shown and described.

DESCRIPTION

FIG. 1 is a perspective view of the nozzle showing the new design;

FIG. 2 is a left elevation view thereof;

FIG. 3 is a right elevation view thereof;

FIG. 4 is a front elevation view thereof;

FIG. 5 is a rear elevation view thereof;

FIG. 6 is a bottom plan view thereof;

FIG. 7 is a top plan view thereof; and,

FIG. 8 is a front elevation view thereof showing tubes interconnected thereto.

The broken lines in the drawings depict unclaimed environmental subject matter.
